Patented Mar. 2, 1971

220,034

VACATION HOUSE

William S. Bowers, 22800 76th W.,
Edmonds, Wash. 98020

Filed Nov. 3, 1969, Ser. No. 19,919

Term of patent 14 years

Int. Cl. D25—04

U.S. CL. D13—1

FIG-1

FIG-2

FIG-5

FIG-3

FIG-4

FIG. 1 is an isometric view of a vacation house embodying my new design;

FIG. 2 is a side elevational view thereof;

FIG. 3 is a plan view thereof;

FIG. 4 is an end elevational view thereof;

FIG. 5 is an isometric view of a shorter form of my vacation house.

The side and end not shown in FIGS. 1 and 5 are like the side and end shown.

I claim:

The ornamental design for a vacation house, substantially as shown and described.
